UNITED STATES PATENT OFFICE.

PIETRO V. MARTINO, OF NEW YORK, N. Y.

DESIGN FOR A RECLINING-CHAIR.

44,728.

Specification for Design.

Patented Oct. 14, 1913.

Application filed June 28, 1913. Serial No. 776,441. Term of patent 7 years.

To all whom it may concern:

Be it known that I, PIETRO V. MARTINO, a citizen of the United States, residing at New York, in the county of New York and State of New York, have invented a new, original, and ornamental Design for a Reclining-Chair, of which the following is a specification, reference being had to the accompanying drawings, forming part thereof.

The figure is a perspective view of the chair in its normal position.

I claim:

The ornamental design for a reclining chair as shown.

PIETRO V. MARTINO.

Witnesses:

WARREN E. WILLIS,
ESTHER GENDEL.
